UNITED STATES PATENT OFFICE

ALBERT LÖSCH, OF HAMBURG, GERMANY

DOUBLE-PIN HOLDFAST

Application filed April 23, 1930, Serial No. 446,565, and in Germany April 26, 1929.

This invention relates to a double pin holdfast which serves for holding together wood parts, especially for toys and models of all kinds, and has for its object a convenient connecting member for wood parts of children's building boxes or wood models of all kinds which are again to be separated without difficulty.

According to the present invention the double pin holdfast consists of a double pin which at the middle is firmly seated in one limb of an angular metal member so that the other limb of this member forms a guide for the double pin by bearing closely against one side of one of the wood parts to be connected together by the double pin holdfast.

In the accompanying drawings Figures 1 and 2 show the double pin holdfast in side elevation and in perspective, and Figure 3 shows a number of wood parts connected together by the double pin holdfast.

The double pin *a* is secured at the middle in the centre of one limb *b* of an angular metal member or L-shaped member. When assembling wood parts the second limb *c* of the angular member forms a secure guide for the double pin *a* as it bears firmly against one side of one of the two wood parts to be connected together.

Wood parts connected together by double pin holdfasts as above described are firmly connected together thereby but can subsequently again be easily separated from one another. The limb *b* of the angular member in which the double pin *a* is secured prevents the pin from penetrating too far into the wood.

I claim:—

1. A double pin holdfast for connecting together wood parts, particularly for toys and models of all kinds, comprising an L-shaped member of metal, and a double ended pin secured in the centre of one of the limbs of the L-shaped member.

2. A double pin holdfast for connecting together wood parts, particularly for toys and models of all kinds, comprising an angular member of metal and a double ended pin secured at the middle in the centre of one of the limbs of the angular member, the arrange-

ment being such that the other limb of the angular member forms a guide for the double pin by bearing firmly against one of the sides of one of the members to be connected together by the double pin.

In testimony whereof I have affixed my signature.

ALBERT LÖSCH.
